INVENTOR

William H. Wood

UNITED STATES PATENT OFFICE.

WILLIAM H. WOOD, OF NEW YORK, N. Y.

FEED-WATER HEATER.

SPECIFICATION forming part of Letters Patent No. 319,376, dated June 2, 1885.

Application filed March 5, 1885. (No model.)

To all whom it may concern:

Be it known that I, WILLIAM H. WOOD, of New York, State of New York, have invented certain new and useful Improvements in Feed-

5 Water Heaters; and I do hereby declare that the following is a full, clear, and exact description of the invention, which will enable others skilled in the art to which it appertains to make and use the same, reference being had 10 to the accompanying drawings, which form a part of this specification, and in which—

Figure 1 is a vertical section of my improved feed-water heater. Fig. 2 is a vertical elevation of the heater when put together. Fig. 3 is a 15 plan of the heater A" B". Fig. 4 represents an enlarged drawing of the expansion-ring B. Fig. 5 represents an enlarged drawing of the expansion-ring A.

Like letters of reference indicate corresponding parts in all the figures.

The object of my invention is to improve the construction of jacket and other feed-water heaters; and its nature consists of the more effectual means for providing for the contraction and expansion of the steam pipes or flues in which the exhaust-steam imparts its heat to the water surrounding them, and in providing the said pipes or flues with independent pipe-plates in which the pipes are expanded; 30 in providing an expansion-ring for them and one for the casing inclosing the pipes; in a scum apparatus for the removal of scum; in providing a cast-iron base for the heater, with inlet exhaust-pipes cast in it, and an angular 35 bottom for directing the sediment and dirt to the pipe for its removal, and in combination of parts hereinafter more fully described.

Under the varying circumstances in which feed-water heaters are subjected it is found 40 almost impracticable to keep the steam-pipes tight, owing to the rigid method of securing them in the pipe-plates in which they are expanded. My invention is to provide for the expansion-rings A and B, which are preferably rolled in weldless rings. A is secured 45 to the face of the exhaust-pipe D and to the pipe-plate C, and the expansion-ring B is riveted to the inside casing, E, which is secured to the pipe-plate C', thus allowing the pipes 50 P free expansion and contraction.

The outside casing, F, covering the inner casing, E, forming space for the steam to escape after passing the steam-pipes P, is pro-

vided with outlet-pipe G and man-hole H, for allowing hand-plate J to be removed from 55 the inner casing, E, to examine the expansion-ring A.

As the water is heated in the inner casing, E, the scum and other light particles rise to the top of cylinder, from which it can pass 60 off through the pipe S into the scum apparatus K, so that the scum will be removed through pipe L, keeping the water clear and clean. The heavy particles and sediment contained in the water will sink to the bottom of 65 the cast-iron base D, and can be taken off through the pipe L. The cold water is admitted through the pipe M and the hot water is taken out through the pipe N, and the condense-water from the exhaust-pipe D is taken 70 off through the pipe O.

The proportions of the completed heater will be varied according to the size of the boilers with which they will be used, and according to location or peculiar surroundings, 75 which will somewhat vary the location of the pipe-connections, and the whole will be supported on a cast-iron base.

Having thus described my invention, I claim and desire to secure by Letters Patent of the 80 United States—

1. In a feed-water heater, the combination of the expansion-ring A, the exhaust-pipe D, and the pipe-plate C, substantially as for the purpose shown and set forth. 85

2. In a feed-water heater, the combination of the expansion-ring B, riveted to the casing E, with the pipe-plate C and casing E, substantially as for the purpose shown and set forth.

3. In a feed-water heater, the combination 90 of the pipe-plates C and C' with the casing E, expansion-rings A and B, and the exhaust-pipe D, substantially as shown and set forth.

4. In combination with heater-casing E, the expansion-ring B, the steam-pipes P, the pipe-plates C and C', with the expansion-ring A, and the cast-iron base D, having angular bottom, substantially as for the purpose specified and set forth. 95

In testimony that I claim the foregoing as my own I have hereunto affixed my signature in presence of two witnesses.

WILLIAM H. WOOD.
